UNITED STATES PATENT OFFICE.

DAVID WALKER, OF NEWARK, NEW JERSEY.

DESIGN FOR A STAIR-CARPET BUTTON.

SPECIFICATION forming part of Design No. 26,107, dated September 29, 1896.

Application filed August 10, 1896. Serial No. 602,361. Term of patent 7 years.

To all whom it may concern:

Be it known that I, DAVID WALKER, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan of the newly-designed stair-carpet button. Fig. 2 is a transverse section of the same on line *x*, and Fig. 3 is a detail section on line *y*.

The leading feature of my design consists in the stair-carpet button ornamented around its center perforation with radiating petal-shaped ornaments which extend out to the periphery of the button, each of the ornaments being convexed longitudinally, as indicated in Fig. 2, and rounded at its extremity, as in Fig. 1.

25

In said drawings, *a* indicates the stair-carpet button, which is circular in general outline. *b* is the central perforation. *c c* are the radiating, raised, and longitudinally-convexed petal-shaped ornaments, extending out to the periphery of the button, as shown. The extremities of the petals are rounded in plan and convexed, as at line *y*, as in Figs. 2 and 3.

35

What I claim is—

The design for a stair-carpet button herein shown and described.

In testimony that I claim the foregoing I have hereunto set my hand this 5th day of 40 August, 1896.

DAVID WALKER.
